JOHN S. LEWIS, OF ELKA DER, IOWA.

Letters Patent No. 95,241, dated September 28, 1869.

IMPROVEMENT IN SEED-PLANTERS.

The Schedule referred to in these Letters Patent and making part of the same.

I, JOHN S. LEWIS, of Elkader, in the county of Clayton, and State of Iowa, have invented a new and useful Improvement in Seed-Planters.

Nature and Objects of the Invention.

My invention relates to that class of seed-planters adapted for sowing small seed, such as clover, broadcast.

The first part of my invention consists in making seed-planters of the class named in the form of a long tubular box, provided with suitable means for the introduction and discharge of the seed, adapted for attachment to the shoulders of a man, being supported in a horizontal position, and operating to discharge the seed by being simply swung or jerked back and forth during the operation.

The second part of my invention consists in forming the seed-box of such seed-planter, and providing it with proper dividing partitions, by uniting, similarly to joints of stove-pipe, a number of short tapering tubes, having their smaller ends only closed, except the last one, with its large end outward, which is closed at both ends, the manufacture of such box being thus rendered simple and easy.

Description of Drawings.

In the accompanying drawings—

Figure 1 represents a perspective view of a seed-planter constructed according to my invention.

Figure 2, a longitudinal section of a portion of the same on an enlarged scale.

Figure 3, a transverse section on the same scale as fig. 2, taken at *z z*, fig. 1, looking in the direction of the arrow.

Similar letters of reference indicate like parts in the several figures.

General Description.

In the drawing—

A represents the long tubular box forming the body of the planter.

B B', respectively, the openings provided for the ingress and egress of the seed.

C C', removable slides for covering the apertures *B B'*.

a a' a', cleats or guides for the support of the slides *C C'*.

b b, perforations in the slides *C'*, for the passage of the seed.

D D, partitions provided to divide the interior of the box *A* into compartments, to equalize the discharge of seed.

E E, the straps for suspending the box *A* from the shoulders of the operator.

F F, loops or handles, by which to agitate and assist in supporting the box.

c c and *d d*, retainers or guides for supporting laterally the straps *E F*.

z z represent the tapering sections, of which the box *A* is preferably composed, and of which the partitions *D* and the end ** of the box* are the bottoms, formed in one part with them, or applied previously to their union. The other end of the box is applied to the open end of the section, at that extremity, before or after such section is applied. These sections are united by the insertion of the smaller end of one into the larger of the other, and securing them in any suitable manner.

The entire apparatus, with the exception of the supporting-straps and handles, which may be of leather, is preferably made of tin or other suitable sheet-metal.

The measurements of the seed-box are preferably about as follows:

Length, sixteen feet; thickness or diameter, three inches; diameter of perforations *B B'*, one inch; length of sections, one foot.

The length of the straps *E F*, of course, vary with the height, &c., of the person using it, and may be made adjustable in length, by any suitable means, if preferred.

The size of the perforations *b*, in the slide *C'*, will vary according to the kind of seed to be sown, and the number in the slide will be varied according as thicker or thinner sowing is desired. Different sets of such slides, with the perforations graduated, both as regards size and number, may accompany each apparatus.

The apertures *B* and their accessories may be dispensed with, and the seed introduced through *B'*, by withdrawing the slides *C*, and the number of said apertures *B'* and their covering-slides may be increased if desired; or, the perforations *b*, of a fixed gauge, may be made in the bottom of the box *A*, and the apertures *B*, with their slides *C*, employed alone.

Any desired variation of the precise proportions and shape of the apparatus named and represented, less than would involve change of principle, may also obviously be made.

Operation.

The compartments of the box *A* being filled with seed, and the slides *C'* with the proper gauge of discharge *b* inserted in the brockets *a'*, the apparatus is attached to the person of the operator, by suspension by means of the straps *E*, from his shoulders. The straps or handles *F* are taken hold of, and the operator, starting, swinging or jerking the box from side to side by means of the handles *F*, the planting is effected. It is apparent that by this means a field may be sown with great rapidity and regularity.

Claims.

I claim as new—

1. A seeding-machine, consisting of a long tubular box, A, provided with apertures B B', (either or both,) covered by slides C C', and with discharge-perforations b, adapted for suspension from the person of the operator by straps E, and provided with handles F, by which to vibrate it, substantially as herein set forth.

2. In combination with the seed-box A, constructed otherwise, and adapted to operate substantially as herein set forth, the partitions D, as and for the purpose explained.

3. The partitioned seed-box A D, composed of tapering sections x, as represented and described, for the purpose set forth.

To the above specification of my improved seed-planter, I have signed my hand, this 29th day of June, A. D. 1869.

JOHN S. LEWIS.
